UNITED STATES PATENT OFFICE.

HERMAN R. ISLER, OF NORWOOD, OHIO, ASSIGNEE TO THE OAKLEY MACHINE TOOL COMPANY, OF CINCINNATI, OHIO, A CORPORATION OF OHIO.

GRINDING-MACHINE.

1,249,632.

Specification of Letters Patent. Patented Dec. 11, 1917.

Application filed March 15, 1917. Serial No. 155,074.

To all whom it may concern:

Be it known that I, HERMAN R. ISLER, a citizen of the United States, and a resident of Norwood, in the county of Hamilton and State of Ohio, have invented certain new and useful Improvements in Grinding-Machines, of which the following is a full, clear, and exact description, reference being had to the accompanying drawings, forming a part of this specification.

My invention relates to improvements in grinding machines, and particularly to the provision of a combined screw and rack feed mechanism therefor.

For certain classes of work, as for instance cylindrical and some classes of surface and internal grinding, a slow screw feed is desirable. For other classes of work, as for instance in sharpening cutters, a quick lever feed is preferable.

One of the objects of my invention is to provide mechanism for both screw and rack or lever feeds of simple, efficient and inexpensive construction.

A further object of my invention is to provide in a grinding machine, the table of which has both screw and rack or lever feeds, means whereby the screw feed may be disengaged.

A further object of my invention is to provide combined feed mechanism for the table of a grinding machine so constructed as to permit convenient operation from various parts of said machine.

Further objects of my invention will be obvious from the following specification thereof, taken in connection with the accompanying drawings, wherein one embodiment of the principle of my invention is particularly disclosed.

In the drawings:

Figure 1 is a front elevation of a grinding machine constructed in accordance with my invention.

Fig. 2 is a plan view of said machine, part being broken away for the sake of clearness.

Fig. 3 is a detail longitudinal section of the feed mechanism.

Fig. 4 is a detail cross section of said feed mechanism.

Fig. 5 is an elevation of one of the threaded jaws.

Fig. 6 is a cross section taken on the line 6-6 of Fig. 5.

Fig. 7 is an elevation of the cam block.

Fig. 8 is an end view of said cam block.

Fig. 9 is a perspective of a portion of the bushing showing the shoulders for limiting the rotation of the cam block.

The numeral 1 indicates the standard or 60 column of a grinding machine on the top of which is a head 2 for the grinding spindle 3. Mounted on said column is an adjustable knee 4 which carries the usual table 5, the latter being adjustable to bring work supported between the head-stock 6 and tail-stock 7, in conjunction with adjustments of the knee, into position to be operated upon by a grinding wheel mounted on the spindle 3. A shaft 8 is journaled in bearings in the 70 saddle of the knee 4 in the usual manner and has rigidly secured to it a spur wheel 9 which is arranged to engage a rack bar 10 secured to the underside of the table 5. An operating lever 11 is provided for the ends of the 75 shaft 8.

Rotatably mounted in bearings 12 at the ends of the table and on the underside thereof, is a shaft 13, the said shaft being provided with a threaded portion 14. One end 80 of said shaft is provided with a hand wheel 15 for the operation thereof. The saddle of the knee 4 is provided with a bore within which a bushing 16 is secured. Rotatably mounted in said bushing is a shaft 17, the 85 inner end of said shaft being journaled in a bearing 18 of one of the jaws hereinafter described. Secured to the outer end of the shaft 17 is an operating lever 19. Mounted on the shaft 17 and secured thereto by means 90 of a screw 20 is a cylindrical cam block 21 provided with oblique slots or cam surfaces 22. The inner end of the bushing 16 is cut away to form shoulders 23 against which a pin 24 secured in the end of the block 21 is 95 arranged to strike during the rotation of the shaft 17, thus limiting the movements of the shaft and block 21 for the purpose herein-after mentioned. Mounted in the frame of the knee 4 at opposite sides of the shaft 17 100 are rods 25; slidably mounted on the said rods are threaded jaws 26, the said jaws being located on opposite sides of the threaded portion 14 of the shaft 13. The lower portions of the jaws 26 are cut away as shown 105 at 27 to provide clearance for the block 21. Secured in the underside of each of the jaws is a pin 28; the said pins are arranged to engage respectively in the slots 22 of the block 21. The threaded portions 29 of the jaws 110

26 are arranged to engage the thread 14 of the shaft 13.

Arrangement is made for the operation of the threaded shaft 13 by means of the hand wheel 30 which operates through appropriate gearing, not particularly disclosed, located in the housing 31, the nature of which may be varied as will be readily understood. The lever 11 for the operation of the shaft 10 8 is detachable and arrangement is made for its use on either end of said shaft for the operation of the rack feed.

The above described mechanism, as will be seen, provides for both screw and rack feeds of the table, the screw feed operating by the engagement of the threaded portions 29 of the jaws 26, with thread 14 of the shaft 13. The engagement of the jaws with the thread 14 is effected by the rotation of the shaft 17 and cam block 21, the jaws being caused to slide upon the rods 25 by reason of the engagement of the pins 28 in the slots 22 of the cam block. Movement of the cam block in one direction, by bringing converging portions of the slots 22 to bear upon the pins 28, causes the jaws 26 to engage the thread 14. Conversely, movement of the block 21 in the opposite direction causes the jaws to open, thus releasing the shaft 13.

30 The pin 24 by striking against the shoulders 23 limits the movement in either direction of the jaws, and thus prevents said jaws from gripping the shaft too tightly, and binding. When the jaws are thus open and 35 the shaft 13 released, the rack feed by means of the gear 9 and rack 10 may be used. It will further be seen that by the arrangement of operating means for the shafts 8 and 13, the feed mechanism for the table may be operated at various convenient points.

Having thus fully described my invention, what I claim as new and desire to secure by Letters Patent is:

1. In a grinding machine, the combination with the table of said machine, of feed mechanism for said table, said mechanism comprising a rotatably mounted threaded shaft, movably mounted engaging means, one of said elements being mounted on said table and the other on the support therefor, means for the rotation of said shaft, a block rotatably mounted adjacent said engaging means, said block being provided with cam surfaces, means on said engaging means arranged to engage said cam surfaces whereby upon the rotation of said block, said engaging means may be caused to engage or disengage said threaded shaft, substantially as and for the purpose described.

60 2. In a grinding machine, the combination with the table of said machine, of feed mechanism for said table, said mechanism comprising a rotatably mounted threaded shaft, movably mounted threaded jaws, one of said elements being mounted on said table

and the other on the support therefor, means for the rotation of said shaft, a block rotatably mounted adjacent said threaded jaws, said block being provided with cam surfaces, means on said threaded jaws arranged to engage said cam surfaces whereby upon the rotation of said block, said threaded jaws may be caused to engage or disengage said threaded shaft, substantially as and for the purpose described. 75

3. In a grinding machine, the combination with the table of said machine, of feed mechanism for said table, said mechanism comprising a rotatably mounted threaded shaft, movably mounted threaded jaws, one of said elements being mounted on said table and the other on the support therefor, a block rotatably mounted adjacent said jaws, said block being provided with cam surfaces, means to limit the rotation of said block, and means on said jaws arranged to engage said cam surfaces, whereby upon the rotation of said block, said jaws may be caused to engage or disengage said threaded shaft, substantially as and for the purpose described. 80

4. In a grinding machine, the combination with the table of said machine, of feed mechanism for said table, said mechanism comprising a threaded shaft rotatably mounted on said table, rods mounted on the support for said table, threaded jaws slidably mounted on said rods, a shaft rotatably mounted in said support between said rods, a block secured to said shaft adjacent said jaws, said block being provided with cam surfaces and means on said jaws arranged to engage said cam surfaces whereby upon the rotation of said block, said jaws may be caused to engage or disengage said threaded shaft, substantially as and for the purpose described. 85 90

5. In a grinding machine, the combination with the table of said machine, of feed mechanism for said table, said mechanism comprising a threaded shaft rotatably mounted on said table, rods mounted on the support for said table, threaded jaws slidably mounted on said rods, a shaft rotatably mounted in said support between said rods, a block secured to said shaft adjacent said jaws, said block being provided with cam surfaces, means to limit the rotation of said block, and means on said jaws arranged to engage said cam surfaces, whereby upon the rotation of said block, said jaws may be caused to engage or disengage said threaded shaft, substantially as and for the purpose described. 95 100 105

6. In a grinding machine, the combination with the table of said machine, of feed mechanism for said table, said mechanism comprising a rack bar, a gear, one of said elements being mounted on said table and the other on the support therefor, means for 110 115 120 125 130

the rotation of said gear to operate said table, a rotatably mounted threaded shaft, movably mounted engaging means, one of said elements being mounted on said table 5 and the other on the support therefor, means for the rotation of said shaft, and means whereby said engaging means may be caused to disengage said threaded shaft, substantially as and for the purpose described.

7. In a grinding machine, the combination with the table of said machine, of feed mechanism for said table, said mechanism comprising a rack bar, a gear, one of said 15 elements being mounted on said table and the other on the support therefor, means for

the rotation of said gear to operate said table, a rotatably mounted threaded shaft, movably mounted threaded jaws, one of said elements being mounted on said table and 20 the other on the support therefor, means for the rotation of said shaft, a block rotatably mounted adjacent said threaded jaws, said block being provided with cam surfaces, means on said threaded jaws arranged to engage said cam surfaces, whereby, upon the rotation of said block, said threaded jaws may be caused to engage or disengage said threaded shaft, substantially 25 as and for the purpose described.

HERMAN R. ISLER.
